The ornamental design for a dispenser, as shown and described.

DESCRIPTION

FIG. 1 is an isometric view of a top, front, and right side of an ornamental design for a dispenser;

FIG. 2 is a front elevational view of the dispenser of FIG. 1;

FIG. 3 is a rear elevational view of the dispenser of FIG. 1;

FIG. 4 is a right side elevational view of the dispenser of FIG. 1;

FIG. 5 is a left side elevational view of the dispenser of FIG. 1;

FIG. 6 is a top plan view of the dispenser of FIG. 1; and, FIG. 7 is a bottom plan view of the dispenser of FIG. 1. The broken lines are included for the purpose of illustrating portions that form no part of the claimed design. The claimed portion extends between the lowermost solid line and the upper shade lines adjacent the dash-dash-dash lines, and between the shade lines adjacent the dash-dash-dash lines on a right side of the dispenser and the shade lines adjacent the dash-dash-dash lines on a left side of the dispenser.
